UNITED STATES PATENT OFFICE.

BERTRAM NORTON, OF DUDLEY, ENGLAND.

RECIPROCATING CONVEYER OR SCREEN.

1,146,947.

Specification of Letters Patent.

Patented July 20, 1915.

Application filed July 10, 1912. Serial No. 708,593.

To all whom it may concern:

Be it known that I, BERTRAM NORTON, a subject of the King of Great Britain, residing at Castledale, Dudley, Worcestershire, England, have invented new and useful Improvements in Reciprocating Conveyers or Screens, of which the following is a specification.

My invention relates to reciprocating conveyers or screens.

It has for its object a reduction of the motive power required to cause the reciprocation.

In the following description and claims, wherever the word conveyer is used it is intended to apply equally to a screen. The reciprocating part of a conveyer in all known cases moves with a variable velocity, generally with the highest velocity occurring at or near the center of the stroke. It is obvious that energy must be imparted to a reciprocating part during the first part of the stroke, (hereinafter referred to as the acceleration period) that is, up to the point of highest velocity, and from this point onward (hereinafter referred to as the retardation period) to the end of the stroke the kinetic energy of the reciprocating part has to be absorbed.

My invention consists of a device for absorbing the kinetic energy of the reciprocating part during the retardation period, converting it into potential energy, and later, after reversal of direction, reconverting it into kinetic energy during the acceleration period. This has the effect of reducing the friction of the working parts of the driving mechanism with a consequent reduction of the motive power required. In order to effect this I connect a reciprocating part to a piston or diaphragm so that the motion of the part causes such piston or diaphragm to compress a volume of air, steam, or other gas within a vessel during the retardation period, thus absorbing the kinetic energy of the reciprocating part and converting it into potential energy. On reversal of the stroke the pressure of the gas reacts through the piston or diaphragm on to the reciprocating part thus assisting the driving mechanism during the acceleration period of the subsequent stroke. In some cases it is advantageous to supply air, steam, or gas to the cylinder or vessel from a source of supply at a pressure greater than atmospheric pressure.

In the drawings Figure 1 is a side elevation and Fig. 2 is a plan of a conveyer. Fig. 3 is a side elevation and Fig. 4 a plan of the compressor cylinder to a larger scale. 60 Figs. 5, 6, 7, 8, 9, 10, 11, 12 and 13 show modifications.

The conveyer *a* is made in two parts *a*¹ *a*² mounted on pivoted arms *b*¹ *b*¹ and *b*² *b*². The parts *a*¹ *a*² are connected together by a lever *c* pivoted at *c*¹, and connected to the part *a*¹, the end of the lever *c* and the part *a*² being connected together by a link *d*. The part *a*¹ is connected to the piston *e* of the cylinder *e*¹ by means of rods *f* *f* and a gudgeon pin *f*¹ passing through the piston and extending at each end through slots *e*² *e*² in the walls of the cylinder which is constructed as shown without stuffing boxes. 70

Fig. 5 shows the conveyer *a* connected by 75 the piston rod *e*³ to the piston *e* of a double acting cylinder *e*¹. Fig. 6 shows a similar arrangement but in this case the conveyer *a* is connected to the cylinder *e*¹ the piston *e* being fixed. In each of the above arrangements the mechanism is shown with the reciprocating part in the position occupied when moving at its highest velocity, the piston being in such a position in the cylinder that it is in equilibrium so far as the air or other pressure in the cylinder is concerned. During the later part of the stroke or retardation period in either direction, the air or other gas is caused to be compressed on one side of the piston up to the end of the stroke. On reversal of direction the compressed gas expands and forces the piston toward the middle of the cylinder, thus assisting during the acceleration period of the ensuing stroke. 85

Figs. 7 and 8 show arrangements similar to Figs. 5 and 6 except that the cylinders are single acting, so that air or gas is compressed during half the forward or backward movement of the conveyer and expands during the other half of the backward or forward movement respectively. 95

In order that any leakage that may take place past the piston or piston rod shall be automatically made good at each stroke a port *g* is provided in the wall of the cylinder so that when the piston is in a position farthest from one end of the cylinder, this port offers a fair way for more air or gas to enter the cylinder as is shown in Figs. 5 110 to 8. In Figs. 3 and 4 the slots *e*² *e*² serve this purpose.

In Figs. 9 to 13 the cylinders are in communication with a source of air supply at greater pressure than atmospheric pressure. In Fig. 9 the conveyer *a* is connected to a *T* lever *h* capable of oscillating on a fixed fulcrum *h*¹. *i* and *j* are cylinders connected by pipes *i*¹ and *j*¹ to a source of pressure supply *k*. Rods *i*² and *j*² connected to the pistons in the cylinders *i* and *j* are in contact with the lower arms of lever *h* and are alternately pressed inward as the lever oscillates. In Fig. 10 a projection *l* on the conveyer is arranged between the ends of the rods *i*² and *j*² and act in a similar manner. In Fig. 15 9 the conveyer *a* is shown in the position occupied when moving at its highest velocity. Further movement to the left causes lever *h* to depress piston against the pressure of gas in cylinder *i*, thus absorbing the kinetic energy of the conveyer during the retardation period. After reversal of direction of stroke the pressure of the gas acting on the piston assists in accelerating the motion of the conveyer during the acceleration period. This action ceases when the conveyer again reaches the position shown in Fig. 9. Subsequent movement toward the right which occurs during a retarding period causes the piston in the cylinder *j* to be depressed. In Fig. 10 the action of acceleration and retardation of part *a* is similar to that in Fig. 9. Fig. 11 is a side view wherein the conveyer *a* is connected to a lever *m* which oscillates about the fixed fulcrum *m*¹ and is jointed to the piston rod *n* of a cylinder *n*¹ oscillating on a fixed pivot *n*². *n*³ is a pipe connecting the cylinder to a source of pressure supply *k*. Any movement of the conveyer toward the left causes piston *n* in the cylinder *n*¹ to be raised against the pressure of the air in the cylinder thus retarding the conveyer *a*. Upon reversal of stroke the pressure of the gas in the cylinder *n*¹ acting upon piston assists to give motion to the conveyer during the acceleration period. Further movement to the right again raises piston, the actions of retardation and subsequent acceleration after reversal being repeated exactly as described above. Fig. 12 is a side elevation and Fig. 13 is an end elevation wherein the conveyer *a* is connected by a link *o* to a crank pin *p* to which is also connected a rod *q* jointed to the piston *r* in the cylinder *r*¹. *s* is a short lever which oscillates about a fixed point *s*¹ and carries at its other end the crank pin *p*. *r*² is a pipe connecting the cylinder to a source of pressure supply *k*. When the conveyer *a* moves to the left (during a retardation period) it constrains the crank pin *p* to move in the same direction, thus causing piston in the cylinder *r*¹ to descend against the pressure in the cylinder. After reversal of direction (that is during the ensuing acceleration period) the pres-

sure in the cylinder acting upward through piston causes the rod *q* to move toward the position shown, in this manner assisting to accelerate the conveyer *a*.

In Figs. 9 to 13 a non-return valve may be provided between the inlet pipe and the cylinder, in such a manner that no return of gas from the cylinder can take place, such a valve is shown at *n*. Thus the inward movement of the piston would cause the pressure in the cylinder to rise above the normal. The pressure from the source of supply must be maintained in the inlet pipe so that any leakage past the piston may be made good. In cases where steam pressure is used this make-up will be necessary on account of condensation in the cylinder.

In the claims air is intended to include gas or steam.

What I claim is:—

1. In combination with a reciprocating conveyer, means for positively driving the same, means actuated by the conveyer for compressing air during half the movement in one direction of the conveyer and arranged so that the compressed air acts to assist the motion of the conveyer during the same half of the movement in the other direction.

2. In combination with a reciprocating conveyer, means for positively driving the same, means for compressing air actuated by the conveyer as it moves in both directions and arranged so that the compressed air acts to assist the motion of the conveyer during the acceleration period in both directions.

3. In combination with a reciprocating conveyer, means actuated by the conveyer for compressing air during half the movement in one direction of the conveyer and arranged so that the compressed air acts to assist the motion of the conveyer during the same half of the movement in the other direction, and means for supplying air at a pressure greater than atmospheric pressure to the means for compressing the air.

4. In combination with a reciprocating conveyer, means for compressing air actuated by the conveyer as it moves in both directions and arranged so that the compressed air acts to assist the motion of the conveyer, and means for supplying air at a pressure greater than atmospheric pressure to the means for compressing the air.

5. A reciprocating conveyer, a cylinder, a piston in the cylinder, means for connecting the conveyer to the piston, and means for supplying air at a pressure greater than atmospheric pressure to the cylinder.

6. The combination of a conveyer, means for positively driving the same, pivoted arms supporting the conveyer, and means attached to the conveyer for compressing air during half the movement in one direction of the conveyer and arranged to cause the com-

pressed air to assist the motion of the conveyer during the same half of the movement in the other direction.

7. The combination of a conveyer, means for positively driving the conveyer, pivoted arms supporting the conveyer and means for compressing air actuated by the conveyer as it moves in both directions and arranged to cause the compressed air to assist the motion of the conveyer in both directions.

8. A conveyer, means for positively driving the same, pivoted arms supporting the conveyer; the driving means and pivoted arms being so arranged that the conveyer reaches its highest point at the movement of its greatest velocity and means actuated by the conveyer for compressing air during half the movement in one direction of the

conveyer and so arranged that the compressed air acts to assist the motion of the conveyer during the same half of the movement in the other direction.

9. A conveyer, means for positively driving the same, pivoted arms supporting the conveyer; the driving means and pivoted arms being so arranged that the conveyer reaches its highest point at the moment of its greatest velocity, means for compressing air actuated by the conveyer as it moves in both directions and so arranged that the compressed air acts to assist the motion of the conveyer in both directions.
